UNITED STATES PATENT OFFICE.

WILLIAM D. JOHNSON, OF MEADOW LANDS, PENNSYLVANIA.

RAIL-JOINT.

SPECIFICATION forming part of Letters Patent No. 789,031, dated May 2, 1905.

Application filed January 23, 1905. Serial No. 242,286.

To all whom it may concern:

Be it known that I, WILLIAM D. JOHNSON, a citizen of the United States of America, residing at Meadow Lands, in the county of Washington and State of Pennsylvania, have invented 5 certain new and useful Improvements in Rail-Joints, of which the following is a specification, reference being had therein to the accompanying drawings.

This invention relates to certain new and useful improvements in rail-joints, and has for its object the provision of novel means whereby the confronting ends of two rail-sections can be joined together without the use 15 of nuts and bolts.

Another object of this invention is to provide a novel form of chair for retaining the confronting ends of two rail-sections together and preventing any lateral movement of said 20 rail-sections.

A further object of this invention is to provide a rail-joint having a continuous tread which will dispense with the pounding of the wheels of the rolling-stock passing over said 25 joints.

The invention finally consists in the novel construction, combination, and arrangement of parts, which will be hereinafter more fully described and then specifically pointed out in 30 the claims, and, referring to the drawings accompanying this application, like numerals of reference designate corresponding parts throughout the several views, in which—

Figure 1 is a top plan view of my improved rail-joint, illustrating the confronting ends of three sections of rails. Fig. 2 is a vertical sectional view of my improved rail-joint. Fig. 3 is a horizontal sectional view taken on the line $x-x$ of Fig. 2, and Fig. 4 is a perspective 35 view of a portion of my improved rail-joint.

To put my invention into practice I employ a specially-constructed rail-section, which is designated by the reference-numeral 1. In rolling my improved rail-sections I split the 40 web portion thereof, forming a groove 2 longitudinally of said rail. In forming this groove the web portions 3 3 of the rail-sections are bent outwardly, forming the sides of said groove tapering, and in said groove is 45 adapted to seat a tapering bar 4.

In the placing of rail-sections upon a road-bed I arrange the bars 4 whereby the confronting ends of said bars will lie intermediate the ends of the adjoining rail-section, this construction being illustrated in Fig. 1 of 55 the drawings.

To retain the confronting ends of the rail-sections in close proximity to one another, I employ a chair 5, the sides 6 of said chair being adapted to overlie the base portions 7 7 of the rail-sections. To brace the confronting ends of two rail-sections, I form the outer edges of the base portions 7 of each confronting end of the rail-sections with beveled faces 8 8. These faces are adapted to engage bevelled faces 9 9, formed centrally within the chair 5, said faces 9 being formed by providing material between the sides 6 and the base of the chair.

By referring to Fig. 3 of the drawings it 70 will be observed that the ends of the adjoining rail-sections are held in close proximity to one another by the chair 5, and any lateral movement of said rail-sections will be prevented by the chair 5 and by the tapering bar 75 4, which engages both rail-sections. This bar is adapted to support the heads or treads of the rail-sections, and where a joint occurs between said sections the tapering bar 4 practically forms a continuous tread, it being impossible 80 for any independent vertical movement of either one of the confronting rail-sections.

While I have herein shown the preferred manner of constructing my improved rail-joint, it is obvious that various changes may be made in the details of construction without departing from the general spirit and scope 85 of the invention.

What I claim, and desire to secure by Letters Patent, is—

1. The combination with a rail having a tapering groove in the web and having its base-flanges sheared at the ends, of a tapering bar fitting in said groove, and a chair receiving 95 the end of said rail with the lower face of the bar resting on said chair, said chair having beveled interior faces to engage the sheared faces of the rail-flanges.

2. In a rail-joint, the combination with a 100

plurality of rail-sections, the web portions of said rail-sections having tapering grooves formed therein, of a tapering bar adapted to seat within the tapering grooves of two of 5 said rail-sections, said bar being adapted to span the joint between said rail-sections, a chair, said chair having beveled faces formed therein, the ends of said rail-sections having their bases sheared to form beveled faces

adapted to engage the beveled faces of said 10 chair, substantially as described.

In testimony whereof I affix my signature in the presence of two witnesses.

WILLIAM D. JOHNSON.
